(57) **CLAIM**

The ornamental design for a computer stand, as shown and described.

DESCRIPTION

FIG. 1 is a perspective view showing our new design for a computer stand;

FIG. 2 is a front view of the stand of FIG. 1;

FIG. 3 is a side view of the stand of FIG. 1, the opposite side view being a mirror image thereof;

FIG. 4 is a rear view of the stand of FIG. 1;

FIG. 5 is a top view of the stand of FIG. 1;

FIG. 6 is a bottom plan view of the stand of FIG. 1;

FIG. 7 is a perspective view of a second embodiment of the stand of FIG. 1;

FIG. 8 is a front view of the stand of FIG. 7;

FIG. 9 is a side view of the stand of FIG. 7, the opposite side view being a mirror image thereof;

FIG. 10 is a rear view of the stand of FIG. 7;

FIG. 11 is a top view of the stand of FIG. 7; and,

FIG. 12 is a bottom plan view of the stand of FIG. 7.

The dashed lines are for illustrative purposes only and form no part of the claimed design, the illustrated hatching of FIGS. 1-6 is continuous across the surfaces on which it appears, and the illustrated hatching of FIGS. 7-12 is shown in dashed lines and forms no part of the claimed design.
